US0D1051608S

(12) **United States Design Patent** (10) **Patent No.:** **US D1,051,608 S**
(45) **Date of Patent:** **** Nov. 19, 2024**

(54) **HANDLE FOR BATTERY OPERATED
TOOTHBRUSH**

2200/1066; A46B 2200/1073; A46B
2200/108; A46B 2200/30; A61C 17/00;
G09B 19/0084

See application file for complete search history.

(71) **Applicant:** **The Gillette Company LLC**, Boston,
MA (US)

CLAIM

The ornamental design for a handle for battery operated toothbrush, as shown and described.

DESCRIPTION

FIG. 1 is a perspective view of a first embodiment of a handle for battery operated toothbrush;
FIG. 2 is a front view thereof;
FIG. 3 is a right side view thereof;
FIG. 4 is a rear view thereof;
FIG. 5 is a left side view thereof;
FIG. 6 is a top plan view thereof; and
FIG. 7 is a bottom view thereof.
FIG. 8 is a perspective view of a second embodiment of a handle for battery operated toothbrush;
FIG. 9 is a front view thereof;

FIG. 10 is a right side view thereof;
FIG. 11 is a rear view thereof;
FIG. 12 is a left side view thereof;
FIG. 13 is a top plan view thereof; and
FIG. 14 is a bottom view thereof.
FIG. 15 is a perspective view of a third embodiment of a handle for battery operated toothbrush;
FIG. 16 is a front view thereof;
FIG. 17 is a right side view thereof;
FIG. 18 is a rear view thereof;
FIG. 19 is a left side view thereof;
FIG. 20 is a top plan view thereof; and
FIG. 21 is a bottom view thereof.
FIG. 22 is a perspective view of a fourth embodiment of a handle for battery operated toothbrush;
FIG. 23 is a front view thereof;
FIG. 24 is a right side view thereof;
FIG. 25 is a rear view thereof;
FIG. 26 is a left side view thereof;
FIG. 27 is a top plan view thereof; and
FIG. 28 is a bottom view thereof.
FIG. 29 is a perspective view of a fifth embodiment of a handle for battery operated toothbrush;
FIG. 30 is a front view thereof;
FIG. 31 is a right side view thereof;
FIG. 32 is a rear view thereof;
FIG. 33 is a left side view thereof;
FIG. 34 is a top plan view thereof; and,
FIG. 35 is a bottom view thereof.
Broken lines are used in the drawings to designate parts of a handle for battery operated toothbrush that form no part of the claim.
